(57) **CLAIM**

The ornamental design for a hair dryer, as shown and described.

DESCRIPTION

FIG. 1.1 is a top-front-left perspective view of a hair dryer showing my new design;

FIG. 1.2 is a front elevational view thereof;

FIG. 1.3 is a rear elevational view thereof;

FIG. 1.4 is a left side elevational view thereof;

FIG. 1.5 is a right side elevational view thereof;

FIG. 1.6 is a top plan view thereof;

FIG. 1.7 is a bottom plan view thereof; and

FIG. 1.8 is a top-front-right perspective view thereof.

The broken lines illustrate portions of the hair dryer that form no part of the claimed design.

1 Claim, 8 Drawing Sheets
